CLOSABLE GOLF PUTTING TARGET

Joseph Niamt, Jr., 1426 26th St., NW, Canton, Ohio
Filed Apr. 13, 1962, Ser. No. 187,258

2 Claims. (Cl. 273—177)

This invention relates to a practice device for enabling golfers to improve their putting.

Various devices have been provided for golfers to practice putting for indoor or outdoor use. Generally, most of such devices have not been satisfactory because they have not sufficiently duplicated the conditions of actual putting on a golf course. Most putting practice devices have included an impediment of one kind or another, such as an inclined plane or other surface different from the shape of the surface on which the device is placed. As a result, the user must apply sufficient force when practicing putting to cause a golf ball to roll up the inclined plane before entering a ball-receiving aperture.

The device of the present invention overcomes the disadvantages of prior putting practice devices by eliminating all inclined planes or other surfaces which would alter the rolling conditions of the ball. The device includes an openable ring comprising two semicircular members which are hinged together in such a manner that when a golf ball rolls into the open ring and strikes the hinge, the ring closes around the ball.

Any golfer desiring to practice putting at home is desirous of duplicating the actual conditions on a putting green as much as possible. That can be done only by putting on a level surface straight into a hole or another target having a level approach. To properly improve one's putting, a golfer should practice with a device that tends to train his vision and to duplicate his "feel" on a normal putting green as much as possible.

Generally, it is an object of this invention to provide a golfer's putting practice device which duplicates as much as practicable the conditions existing on a putting green of a golf course.

It is another object of this invention to provide a putting practice device for a golfer who desires to practice on a surface level path to target.

It is another object of this invention to provide an indoor putting practice device having an opening wide enough to permit entry of a golf ball, which opening substantially duplicates outdoor putting conditions.

It is another object of this invention to provide a putting practice ring having two half-portions hingedly mounted together to permit the members to close together around a ball with a characteristic click when a golf ball is putted directly into the ring.

It is another object of this invention to provide a golfer's putting practice ring which may be used indoors or outdoors and which is therefore of relatively small size to enable ready portability of the ring by carrying it either on the golfer's person or in a golf bag.

Finally, it is an object of this invention to provide an improved device which accomplishes the foregoing desiderata in an inexpensive manner.

These and other objects and advantages apparent to those skilled in the art from the following description and claims may be obtained, the stated results achieved, and the described difficulties overcome by the discoveries, principles, apparatus, parts, elements, combinations, and subcombinations which comprise the present invention, the nature of which is set forth in the foregoing general statements, preferred embodiments of which—illustrative of the best modes in which applicant has contemplated applying the principles—are set forth in the following description and shown in the drawings, and which are particularly and distinctly pointed out and set forth in the appended claims forming part hereof.

2

The nature of the improved golfer's putting practice device of the present invention may be stated in general terms as including a preferably annular ring composed of two half-portions having one pair of adjacent ends hingedly secured together, whereby the other end may be separated by opening the ring to a desired spacing so that the force of a rolling ball against the hinge moves the hinge member a sufficient distance to cause the open ring half-portions to close around the ball.

By way of example, the device of the present invention is shown in the accompanying drawings wherein:

FIGURE 1 is a diagrammatic view of the manner in which the device is used in practice;

FIG. 2 is a plan view of one embodiment of the ring in the open position and showing a golf ball in broken line making initial contact therewith;

FIG. 3 is an elevational view of the ring shown in FIG. 2;

FIG. 4 is a plan view of the ring in the closed position and showing the golf ball in broken lines within the ring;

FIG. 5 is an enlarged vertical sectional view taken on the line 5—5 of FIG. 2;

FIG. 6 is an enlarged elevational view taken on the line 6—6 of FIG. 2;

FIG. 7 is a plan view, partly in section, of another embodiment of the invention, showing the ring in the closed position; and

FIG. 8 is a fragmentary elevational view showing the embodiment of FIG. 7 in the open position similar to the position shown in FIG. 2.

Similar numerals refer to similar parts throughout the various figures of the drawings.

The device of the present invention is an openable ring generally indicated at 1 in the drawings. It is composed of two half-portions 2 and 3 which are secured together by conventional hinge means such as a pin hinge 4 (FIG. 6), which includes a pin 5.

The ring 1 is used by placing it on a level surface such as a floor or rug 6 indoors or on an outdoor surface such as grass. The ring 1 is open to a prescribed distance and a golf ball 7 is putted by a putter 8 toward the open ring 1. The object of each putt is to hit the ball 7 with sufficient force to strike the center of the back edge of the ring where the hinge 4 is located. The force of the ball 7 striking the hinge 4 will cause the hinge 4 to move away from the ball, which in turn brings the open ends 2a and 3a of the half-portions together from the open position of FIG. 2 to the closed position of FIG. 4. It is desirable that the ends 2a and 3a meet with sufficient force to create a satisfying sound.

As shown in FIG. 1, a small flag 9 may be detachably mounted on the ring 1 by providing it as a detachable extension of the hinge pin 5.

The ring 1 may be composed of molded or cast material such as plastic, wood, or hard rubber, but is preferably composed of fabricated sheet metal. In order for it to have the desired weight and rigidity, the substantially similar half-portions 2 and 3 are provided with upper and lower turned-in edges 10, as shown in FIG. 5. The portions of the members 2 and 3 forming the hinge 4 are preferably integral with said portions, as shown in FIG. 6, and the hinge is free-swinging. Any other hinge construction, however, may be used which is free-swinging.

Although the ring 1 basically includes the two half-portions 2 and 3 which are hingedly secured together by a hinge 4 as shown in FIG. 1, the ring may be provided with additional means such as a ball strike bar 11 to facilitate closing of the ring. The bar 11 includes a ball contact end portion 12 as well as an opposite end portion 13 having upper and lower edges secured in place, such as in the upper and lower inturned edges 10 of the member 2. Said portion 13 of the bar 11 is preferably slidably

mounted in position, as shown in FIG. 5, so that the position of the contact end portion 12 may be adjusted from time to time as deemed necessary, such as where the ring is open to a lesser extent than complete opening, as shown in FIG. 2.

The intermediate portion of the bar 11 extends or is inclined inwardly from the end portion 13. The end portion 12 is disposed at the inner end of the intermediate portion of the bar 11 and extends at an angle to the intermediate portion. Thus, a golfer may wish to practice his putting with greater accuracy by opening the ring to a distance only slightly larger than the diameter of the ball. In such event, a slight adjustment in the position of the contact end portion should be made by slidably moving the bar 11 with respect to the half-portion 2.

As shown in FIGS. 2, 4, and 6, a stop member 14 is mounted on the back of the hinge 4 for the purpose of limiting the extent of opening of the ring. The member 14 is secured by a weld 15 (FIG. 6) on one of the hinge members where it serves as a stop to prevent opening of the ring beyond the desired limit. Thus the distance between the spaced ends 2a and 3a, as shown in FIG. 2, is equal to a distance considerably smaller than the diameter of a cup on the green of a golf course. That distance marks the central zone through which the ball must pass in order to assure the ball dropping into the cup when it strikes the back side thereof. Otherwise, if a ball is putted on the outer sides of the zone, the ball may roll with sufficient force around either edge of the cup without dropping in. Accordingly, the distance between the ends 2a and 3a is preferably established by the position of the stop member 14 on the hinge 4. Other means than the stop member 14 may be provided such as a chain extending across the open members 2 and 3, which limits their opening and which closes the members when the ball 7 strikes the chain.

Another embodiment of the invention is shown in FIGS. 7 and 8 in which means for facilitating closing of ring members 2 and 3 include a bar 16 having a target 17 attached to one end portion 18, preferably by spot welding. The target 17 may be round and extends laterally on opposite sides of the end portion 18. An opposite end portion 19 of the bar 16 is preferably seated within upper and lower edges 10 of the half-portion 2 in a manner similar to that shown in FIG. 5.

The bars 11 and 16 are preferably composed of flexible material such as sheet metal which yields slightly upon the ball striking the contact end portion 12 or the target 17 and which upon reflex actuates the half-portions 2 and 3 to close quickly to the position shown in FIG. 4 and thereby help to arrest the movement of the ball 7.

Accordingly, the device of the present invention enables the user to practice putting away from the golf course under conditions which duplicate the conditions found on a putting green as much as possible. That can be done only by putting on a level surface directly into a hole or another level target. The present device enables the user to practice putting by training one's vision and "feel."

Ideal putting procedure requires that the golf ball be aimed toward the back edge center of the cup. The device of the present invention encourages that procedure in order to close the ring around the ball. The idea of hitting the ball with sufficient force to close the ring is intended to train a golfer to putt a ball hard enough to maintain a true line to and into the cup. Weak putts have a tendency to waiver and frequently roll out of line due to various conditions such as grain of the grass, slopes, etc.

Finally, a golfer can reset the putting device quite easily by using his club, making it unnecessary to stoop or even use his hands. He may also face the device in any direction by merely turning it with his extended putter or golf club. More than one device can be used and placed in various locations to further duplicate practice putting conditions and to afford more than one target and to make it unnecessary to constantly retrieve one ball each time. In fact, if the practice area were large enough to make it practical to have a set of nine or eighteen devices, this could create an indoor or outdoor game.

In the foregoing description certain terms have been used for brevity, clearness and understanding, but no unnecessary limitations have been implied therefrom as such words are used for descriptive purposes and are intended to be broadly construed.

Moreover, the embodiment of the improved construction illustrated and described herein is by way of example and the scope of the present invention is not limited to the exact construction shown.

Having now described the invention, construction, operation and use of a preferred embodiment thereof and the advantageous, new and useful results obtained thereby; the new and useful golf putting practice device and reasonable mechanical equivalents thereof obvious to those skilled in the art are set forth in the appended claims.

What is claimed is:

1. A golf training device including two members shaped to jointly encircle a golf ball and having one pair of end portions interconnected by a hinge, the members being rotatable about the hinge and having another pair of end portions movable between opened and closed positions, lever means for closing the members and including a strike bar having one end portion fixedly attached to one member and extending inwardly therefrom, the other end portion of the strike bar being disposed across and spaced from the inner side of the hinge, a target attached to said other end portion of the strike bar, said target extending laterally on opposite sides of said other end portion, whereby striking of the target by a golf ball moves said other end portion to the closed position.

2. A golf training device including two members shaped to jointly encircle a golf ball, a hinge connecting one end of one member to one end of the other member, the members being movable between opened and closed positions, a stop mounted on the hinge for limiting the extent of opening of the members, lever means for closing the members and having one end portion fixedly secured to one of the members and extending radially inwardly therefrom, the other end portion of the lever means being disposed between the hinge and an opening provided by the members in the opened position, a target attached to said other end portion of the lever means, said target extending laterally on opposite sides of said other end portion, whereby the portions move to the closed position when a golf ball rolls against the target.
